UNITED STATES PATENT OFFICE

JAMES D. KRIVE, OF ST. LOUIS, MISSOURI, ASSIGNOR TO INTERNATIONAL SHOE COMPANY, OF ST. LOUIS, MISSOURI, A CORPORATION OF DELAWARE

TREEING JACK

Application filed June 9, 1930. Serial No. 459,888.

This invention relates to treeing jacks for shoes; and an object of the invention is to provide a treeing jack for use in finishing shoes while the original last remains in the 5 shoes during the finishing operation.

Another object of the invention is to provide a machine of the character mentioned having a member constructed and arranged to engage within a socket in the shoe last 10 while the shoe remains on the last, and to support the shoe in a relationship in which the shoe may be turned about the axis of said member and finished while the longitudinal axis of the lasted shoe is approximately radial to the axis of said member, in combination with a pivoted expander for the shoe upper constructed and arranged to extend into the shoe upper and assume proper relationship to the upper portion of the last and 15 to remain in such position during the finishing operation.

Another object of the invention is to provide a machine of the character mentioned having an expander for the shoe upper arranged in the position stated, in combination with an opposing stretching device for engaging the shoe upper so as to stretch and smooth the shoe upper during the finishing 20 operation.

Another object of the invention is to provide an improved treeing jack embodying any or all of the improved features of construction and combinations of elements operating and cooperating for the advantageous 25 purposes herein disclosed, reference being made to the accompanying drawings, in which—

Fig. 1 is a side elevation of my improved machine.

Fig. 2 is a top plan view of the expander for the upper and the adjacent portion of the support therefor.

Fig. 3 is a cross-sectional view approximately on the line 3—3 of Fig. 5.

Fig. 4 is a cross-sectional view approximately on the line 4—4 of Fig. 5.

Fig. 5 is a vertical longitudinal sectional view of the upper end of the machine showing the arrangement of the devices that are operated to obtain gripping engagement in

the socket of a shoe last, and the parts in the positions they occupy when a lasted shoe is supported on the machine.

Fig. 6 is a similar view showing the parts in the positions they occupy when no shoe 55 is on the machine.

The machine in which the present invention is embodied comprises a base 1 having rigid therewith a vertical tubular standard 2 which has a vertical split 3 at its upper end 60 so as to permit said upper end of the standard to be expanded and contracted.

A tubular frame body 4 is mounted on the upper end of the standard 2 by an arm 5 projecting into the upper end of the standard 2 65 and secured therein by a clamp device 6.

A treadle lever 7 is mounted on a rock shaft 8 supported for rocking movements in a bearing 9 rigid on the base 1, and is operative to oscillate a crank arm 10 projecting from said 70 shaft 8 and having pivotal connection with the lower end of a link 11. The upper end of the link 11 is connected by a coupling 12 with the lower end of a link 13 which has its upper end pivoted to the outwardly extended 75 arm 14 of a bell crank lever. This bell crank lever is mounted on a pivot 15 in the body 4 and has an arm 16 bearing against the outer end of a plug 17 screwed in the outer end of a sleeve 18 mounted for sliding movements in 80 the body 4.

A sleeve 19 is mounted for turning movements in the end of the body 4 opposite from the sleeve 18. This sleeve 19 is rotatively held in position in the body 4 by a latch 20 85 having one end mounted on a pivot 21 in a transverse slot in the body 4 and arranged to engage in a circumferential groove 22 in said sleeve 19. This latch 20 may be disengaged from the sleeve 19 to permit the latter 90 to be withdrawn and replaced, as desired.

A shaft 23 is mounted axially within the sleeve 19 and is rigid therewith, so that, when the sleeve is rotated or moved, the shaft 23 must, of necessity, be rotated or moved with 95 said sleeve 19. The inner end of this shaft 23 has an abutment device 24 screwed thereon and located within the sleeve 18. The outer end of the shaft 23 is formed with a clutch portion 25.

A cooperating clutch member 26 is mounted for longitudinal sliding movements in a longitudinal groove 27 formed in the shaft 23. The clutch member 26 is movable longitudinally to position in which its outer end is approximately even with the outer end of the clutch portion 25, in which adjustment the peripheral edge of the clutch member 26 is approximately flush with the peripheral surface of the clutch portion 25. This is for the purpose of forming a round clutch comprising the two parts 25 and 26, so that they may readily be inserted in and withdrawn from a socket 28 in a shoe last 29. When the clutch 15 is in the socket, the clutch member 26 is drawn inwardly and expanded to the position shown in Fig. 6 by co-acting beveled surfaces 30 on said clutch members 25 and 26, as will be readily understood by reference to Fig. 6 of the 20 drawings.

The inner end of the clutch member 26 has a radial projection 31 received in a recess in a sleeve 32 mounted for sliding movements in the body 4 and along the shaft 23 while the shaft 23 remains stationary. A coil spring 33 abuts against the inner end of the sleeve 19 and has a portion thereof enclosed by a cylindrical extension 34 of said sleeve. The opposite end of said spring 33 encircles a cylindrical extension 35 of the sleeve 32. The spring 33 is effective to actuate the clutch member 26 to clutching position (Fig. 6), in which the sleeve 32 is against the abutment 24. The lever 14—16 may be operated to release the clutch by moving the sleeve 18 and the sleeve 32 longitudinally along the shaft 23 to compress the spring 33 and bring the beveled surfaces 30 to position in which the clutch is contracted. When the bell crank lever 14—16 is released, the spring 33 will immediately act to move the clutch member 26 to clutching position. A sleeve 36 telescopes within the outer end of the sleeve 19 and is secured in rigid relationship to said sleeve 19 by a set screw 37 (Fig. 1) mounted in said sleeve 19 and clamping against the sleeve 36.

A pair of bracket arms 38 on the outer end, which is the forward end, of the sleeve 36 supports a pair of aligned guide pins 39, which may be in the form of screws screwed through holes in the arms 38 and having their inner ends projecting beyond the inner surfaces of said arms 38. These pins 39 are in axial alignment with each other and are detachably and adjustably secured in their mountings by their threaded engagement with the arms 38 and by clamping nuts 40 screwed on the outer end of said pins and clamping against the surfaces of the arms 38.

Leg forms of different sizes for shoes having high uppers may be optionally mounted in the machine for cooperation with the last 29 during the finishing operations. By this, 65 it will be understood that leg forms appro-

priate to the size of the shoes that are being finished may be applied to the machine. Each leg form comprises a tubular element including approximately parallel side walls 41 and rounded connections 42 uniting the side walls 41 and cooperating therewith to form an appropriately shaped tube. The walls 41 have widened portions 43 at their forward ends connected by extensions of the walls 42, having a notch 44 in the front wall 42 and a notch 45 in the rear wall 42. The walls 43 flare apart, as shown in Fig. 2 and the notches 44 and 45 receive the front and rear portions of the last 29. The flared wall terminals fit closely and smoothly against the sides of the last so that the high shoe upper extends onto the tube described. A smooth inside filler is thus provided for each shoe, each filler comprising the last 29 cooperating with the tube described. The shoe upper encloses the outer, which is the forward, end of the tube and, in operation, is smoothed on and around the tube by ironing or other appropriate operations.

Each of the leg tubes described has a thick-end portion 46 at its rear end provided with slots 47 receiving the ends of the pins 39. A spring 48 has one end seating against the sleeve 36 and the opposite end bearing against a projection 49 from the upper side of the thickened ring portion 46. The lower end of the spring is held in position by a projection 50 extending into the spring, and the upper end of said spring is held in position by a projection 51 from the extension 49. The power and energy of this spring is exerted to hold the leg tube in position in which the rear portion of the tube is adjacent to the clutch 25. The pins 39 and the slots 47 constitute a peculiar type of pivotal connection for this purpose. The forward end of the leg tube may be manipulated to permit the insertion of the upper portion of the last 29 into the forward end of the tube, thus holding the last and the tube in cooperative relationship so that the shoe may be appropriately smoothed and finished.

An arm 52 has one end attached to the sleeve 36 and the opposite end forming a supporting connection for one end of a strong retractile spring 53. A member comprising a pair of arms 54 is pivotally connected with the opposite end of the spring 53 and has hooks 55 designed and adapted to engage in the eyeleted holes 56 of the shoe upper (Fig. 5) in order to stretch the shoe and hold the shoe properly distended for the finishing operations.

It is now clear that my invention comprises a support 23 that is rotative about an axis, and that said support is provided with cooperative mechanism for engaging the last of the lasted shoe and supporting the lasted shoe for rotation about said axis in a relationship in which the longitudinal axis of

the lasted shoe is approximately radial to the axis of said support. My invention further comprises an expander of novel construction and arrangement for cooeration with the last of the lasted shoe to hold the shoe distended and stretched during the finishing operations, in combination with resilient means comprising the spring 53 for stretching the shoe upper about said expander. Further, my invention comprises the elements indicated in combination with the other cooperative features of the machine herein shown and described.

The preceding description in connection with the annexed drawings make clear the construction and mode of operation of the invention without further specific description thereof. It is clear that the invention may be varied within equivalent limits without departure from the nature and principle of said invention. I do not restrict myself in any unessential respects, by what I claim and desire to secure by Letters Patent is:

1. A machine of the character described comprising a rotative support for engaging the last of a lasted shoe and supporting the lasted shoe for rotation about the axis of said support in a relationship in which the longitudinal axis of the lasted shoe is approximately radial to said axis of said support, a tubular leg expander device, and means pivotally supporting one end of said leg expander device in position to permit the opposite end of said device to enclose the upper portion of the last in the lasted shoe.

2. A machine of the character described comprising a rotative support for engaging the last of a lasted shoe and supporting the lasted shoe for rotation about the axis of said support in a relationship in which the longitudinal axis of the lasted shoe is approximately radial to said axis of said support, a leg expander device, means pivotally supporting one end of said leg expander device in position to permit the opposite end of said device to enclose the upper portion of the last in the lasted shoe, and resilient means for stretching the shoe upper along and about said expander.

3. A machine of the character described comprising means for supporting a shoe last and a shoe mounted thereon for finishing operations, a unitary tubular expander for extension into the shoe upper into engagement with the last, means pivotally supporting one end of said expander, and resilient means for expanding the shoe upper.

4. A machine of the character described comprising mechanism cooperating with the original last of a lasted shoe for supporting the shoe for finishing operations in position in which the shoe is rotative about a horizontal axis in a relationship in which the longitudinal axis of the shoe is approximately radial to the horizontal axis, and a tubular

leg expander pivotally supported at one end and having its opposite end free and arranged to enclose the upper rear portion of the last and form a surface on which the shoe upper may be finished.

5. A machine of the character described comprising mechanism cooperating with the original last of a lasted shoe for supporting the shoe for finishing operations in position in which the shoe is rotative about a horizontal axis in a relationship in which the longitudinal axis of the shoe is approximately radial to the horizontal axis, a tubular leg expander pivotally supported at one end and having its opposite end free and arranged to enclose the upper rear portion of the last and form a surface on which the shoe upper may be finished, and resilient means for expanding the shoe upper along and about said expander.

6. A treeing jack for treeing shoes for finishing operations comprising a support for supporting a last on which the shoe is mounted, a pivoted expander member for extending into the shoe upper, resilient means for actuating said expander member to an ineffective position and yielding to permit said expander member to telescope about the upper portion of the shoe last, and resilient means for engaging and stretching the shoe upper along and about said expander.

7. A treeing jack for treeing shoes for finishing operations comprising a support for supporting a last on which the shoe is mounted, a unitary expander member having one end adapted to telescope about the upper rear portion of the shoe last, and means pivotally supporting the opposite end of said expander member for adjustment to cooperate with the shoe last.

8. A treeing jack for treeing shoes for finishing operations comprising a support for supporting a last on which the shoe is mounted, a unitary expander member having one end adapted to telescope about the upper rear portion of the shoe last, means pivotally supporting the opposite end of said expander member for adjustment to cooperate with the shoe last, and resilient means for engaging and stretching and expanding the shoe upper on and about said expander.

9. A machine of the character described comprising a tubular expander device for shoe uppers, flaring terminal portions on one end of said expander device for receiving between them the upper part of the heel portion of a shoe last, a pivot supporting the opposite end of said device, and a device enclosed in said expander for engaging the last of a lasted shoe and supporting said last and said shoe in a relationship in which the upper part of the heel portion of the last is enclosed in said expander and in which the shoe upper encloses said expander.

10. A machine of the character described

comprising a tubular expander device for shoe uppers, flaring terminal portions on one end of said expander device for receiving between them the upper part of the heel portion of a shoe last, a device enclosed in said expander for engaging the last of a lasted shoe and supporting said last and said shoe in a relationship in which the upper part of the heel portion of the last is enclosed in said 10 expander and in which the shoe upper encloses said expander, a pivotal support for the opposite end of said expander from said flaring portions, and a spring pressing said expander in a direction to cooperate properly 15 with the last of the shoe.

11. A machine of the character described comprising a tubular expander device for shoe uppers, flaring terminal portions on one end of said expander device for receiving 20 between them the upper part of the heel portion of a shoe last, a device enclosed in said expander for engaging the last of a lasted shoe and supporting said last and said shoe in a relationship in which the upper part of 25 the heel portion of the last is enclosed in said expander and in which the shoe upper encloses said expander, a pivotal support for the opposite end of said expander from said flaring portions, a spring pressing said expander in a direction to cooperate properly 30 with the last of the shoe, and resilient means for stretching the shoe upper along and about said expander.

12. A machine of the character described 35 comprising an expander for a shoe upper having notches in one end, flaring portions on said end of said expander at the sides of said notches adapted to receive between them the upper part of the heel portion of a last 40 mounted in a shoe, a rotative support for engaging and supporting the last of a lasted shoe in a relationship in which the longitudinal axis of the shoe is approximately at right angles to the axis of said support, and 45 means for stretching and expanding the shoe upper about said expander.

13. A machine of the character described 50 comprising rotative means for supporting a shoe for finishing operations, a unitary tubular expander for extension into the shoe upper and having opposite notches in one end for receiving a last, means for engaging a last mounted in the shoe to support the shoe in 55 position in which said expander extends into the shoe upper, and resilient means for expanding the shoe upper.

14. A machine of the character described 60 comprising a rotary support cooperating with the original last of a lasted shoe for supporting a shoe for finishing operations in position in which the shoe is rotative about a horizontal axis while the longitudinal axis of the shoe remains approximately radial to said horizontal axis, a tubular leg expander for 65 the shoe arranged to enclose the opposite sides

of the upper rear portion of the last and form therewith an approximately smooth surface on which the shoe may be finished, a resilient device actuating the expander to proper co-operative relationship with the last, and resilient means for expanding the shoe upper 70 along and about said expander.
